(57) CLAIM

The ornamental design for a sock for pilates, yoga, or exercise, as shown and described.

DESCRIPTION

FIG. 1 is a top perspective view of a sock for pilates, yoga, or exercise of the present invention showing my new design with the dotted lines depicting solely environmental structure and forming no part of the claimed design;

FIG. 2 is a bottom plan view thereof;

FIG. 3 is a front end view thereof;

FIG. 4 is a left side elevational view thereof;

FIG. 5 is a top plan view thereof;

FIG. 6 is a right side elevational view thereof; and,

FIG. 7 is a rear end view thereof.
